James H. Pearson

By Robt A. Lacey, ATTYS

UNITED STATES PATENT OFFICE.

JAMES H. PEARSON, OF BLOOMFIELD, INDIANA.

FENCE.

SPECIFICATION forming part of Letters Patent No. 275,940, dated April 17, 1883.

Application filed November 29, 1882. (No model.)

To all whom it may concern:

Be it known that I, JAMES H. PEARSON, a citizen of the United States, residing at Bloomfield, in the county of Green and State of Indiana, have invented certain new and useful Improvements in Fences; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in fences; and it consists in the construction and arrangement of the several parts, as will be hereinafter fully described, and specifically pointed out in the claim.

In the drawings, Figure 1 is a plan view, Fig. 2 is a detail view, and Fig. 3 is an elevation, of a fence constructed according to my invention.

a *a*² designate the panels, composed of the bars *a'* and the posts or battens *a*³ *a*⁴. These battens in the adjacent panels are arranged on opposite sides of the bars, as shown, and are extended a short distance above the upper and below the lower bar of the panel to provide means for securing the link *b* of wire. This link *b* embraces the upper and lower ends of the posts or battens and clamps them tightly together.

In the operation of building my fence I lay the panel *a* in the position indicated in dotted lines at *a*⁵, Fig. 1, with the bars of panel *a* rested against the battens of the panel *a*², as indicated. I then secure the battens of the two panels together by the links *b*, as shown, twisting the links tolerably tight. I then swing the panel *a* around the panel *a*², as shown, until the ends of the bars of the adjacent panels bear against each other in the position shown in Fig. 1, in which position the link of wire will firmly hold them. The fence is thus given the proper worm, and the ends of the adjacent panels being clamped tightly against each other and held in this position by the wire links passed around the battens arranged on opposite sides of the bars, as shown, a firm, solid

fence is furnished—one from which it is almost impossible to knock a bar or board off, and from which the bars cannot be drawn by the action of the sun and rain.

In turning the panels to give the proper worm and to bring the ends of the bars of adjacent panels to bear directly against each other, the wire link is drawn into the battens, so that it will not slip off.

I prefer to place the panels, preparatory to turning, in the position indicated at *a*⁵, Fig. 1; but it will be seen that they may be placed as indicated at *a*⁶ in the same figure.

In a fence thus constructed the vertical battens *a*³ *a*⁴ are secured on the outer side of the panels *a* *a*², and, being brought to the proper worm, as before described, the corners or angles of the boards of the panel *a* will bear against the back of the boards of the panel *a*², and when clamped in this position by the link *b* the boards or bars of each panel will be prevented by the bracing produced by the construction and arrangement shown and described from being knocked off the battens, to which they are secured by any ordinary knock or jar.

Having thus described my invention, what I claim, and desire to secure by Letters Patent, is—

In a fence, the combination of the panel *a*², having the vertical batten *a*⁴ secured across the outer side of the ends of its boards, the panel *a*, having the vertical batten *a*³ secured across the outer side of the ends of its boards, and having the angles or corners of its boards placed against the back of the adjacent panel *a*² opposite to and braced against or in opposition to the batten *a*⁴ thereof, whereby a pivotal movement of the one panel upon the other may be had, and the loop *b* passed around the battens, substantially as set forth.

In testimony whereof I affix my signature in presence of two witnesses.

his
JAMES H. X PEARSON.
mark.
